COMBINED IGNITION AND STARTING SYSTEM FOR INTERNAL-COMBUSTION ENGINES

John Beck, Portage la Prairie, Manitoba, Canada

Application November 12, 1947, Serial No. 785,492

1 Claim. (Cl. 123—179)

1

This invention relates to new and useful improvements and structural refinements in internal combustion engines of automobiles, tractors, boats, or the like, more specifically, in the ignition and starting systems of such engines, and the principal object of the invention is to provide an apparatus of the character herein described whereby the ignition system of the engine will be supplied with current at proper and full voltage, notwithstanding any drain such as may be 10 imposed on the storage battery by the starting motor.

It is well known that the ability of internal combustion engines to start, particularly in cold weather, is considerably hindered, if not totally destroyed, by the demand for current by the starting motor upon the battery, so that only a current of very low voltage, if any, remains available for the energization of the ignition coil and spark plugs. It is therefore, as aforesaid, the principal object of the invention to eliminate this disadvantage by supplying the ignition coil with proper voltage of current while the starter is in operation.

A further object of the invention is to provide an ignition and starting system of the character described, wherein the voltage of current delivered to the ignition coil during the normal running operation of the engine is not excessive, and wherein the voltage of current passing through the coil during starting may be adjusted so as to assure efficient starting of the engine under either summer or winter driving conditions.

Another object of the invention is to provide a combined ignition and starting system for internal combustion engines which includes means for delaying the delivery of current of proper voltage to the ignition coil for a short period after the starting motor switch has been closed and for continuing the supply of such current to the coil for a short period after the switch has been opened, the former arrangements assuring that an increased supply of current is not delivered to the switch prematurely and the latter arrangement assisting in the energization of the coil and spark plugs immediately after the supply of current to the starting motor is discontinued, thereby facilitating quick and easy starting of the engine, particularly in cold temperatures.

An additional object of the invention is to provide a combined ignition and starting system which is simple in construction, which may be effectively employed in association with new engines as well as those already in existence, and which will readily lend itself to economical manufacture.

With the foregoing objects in view, and such other objects and advantages as will become apparent to those skilled in the art to which this

2

invention relates as this specification proceeds, my invention consists essentially in the arrangement and construction of parts all as hereinafter more particularly described, reference being had to the accompanying drawing which is a wiring diagram of the ignition and starting system of an internal combustion engine, embodying the instant invention and arranged in accordance with the teachings thereof.

Referring now to the accompanying drawing, the invention consists of a combined ignition and starting system for an internal combustion engine, the system being designated generally by the reference character 5 and the engine including a conventional storage battery 6, a starting motor 7, a starter motor switch 8, an ignition coil 9 together with a distributor 10, and an ignition switch 11, all these being of conventional type so that detailed description thereof is considered unnecessary.

However, it should be explained that the proper operating voltage of the coil 9 is somewhat lower with respect to the normal output of the battery 6, say 4½ volts and 6 volts respectively, and a relatively strong resistor 12 is connected in series by means of the conductor 13 to the coil and to the battery 6 through the switch 11, so that current from the battery to the coil is reduced to proper (4½ volt) voltage before passing through the coil under normal engine operating conditions.

The starting motor 7 is connected to the battery 6 through the medium of the switch 8 by means of the conductor 14, and the essence of novelty in the invention resides in the provision of means for supplying current of proper, full voltage to the coil 9 while the starter 7 is energized, that is to say, without the necessity of such current passing through the resistor 12.

This means includes a suitable solenoid 15 having a core 16. The winding of the solenoid is connected in parallel, via conductor 17 to the starter 7 and switch 8. The core 16 of the solenoid is also connected via conductor 18 to the switch 8. A yieldable armature 19 is magnetically drawn into contact with core 16 when current is flowing in conductor 17 so that the parts 16 and 19 may, for convenience, be designated as a magnetically operated switch. Armature 19 is also provided with an extension finger 20 carrying a contact point 21 which in turn engages with a stationary contact point 22. The latter is connected by means of a cable 23 to the aforementioned coil 9, a further resistor 24 being interposed in series in the cable 23, as will be clearly apparent. However, it should be noted that the resistor 24 is relatively weak with respect to the resistor 12, the "strength" of the resistor 24 being equal to approximately one half the strength of the resistor 12.

A conductor cable 25, including a switch 26, bridges the resistor 24, matters being so arranged that when the switch 26 is open, current will pass through the resistor 24, but when the switch is closed, passage of current through the cable 25 will be facilitated.

A free extremity of the aforementioned finger 20 operatively engages the teeth of a relatively large gear 27 constituting a component of a train of step-up gears designated generally by the reference character 28. The gear 27 meshes with a pinion 29 secured to a shaft 30 which also carries a gear 31 in mesh with a pinion 32 on a further shaft 33 provided with an escapement wheel 34. The teeth of wheel 34 alternately engage a pair of pins 35 and 36 on a reciprocating balance wheel 37 mounted on shaft 38 thereby providing the required braking action.

The contact points 21 and 22 are normally open, and it will be apparent from the foregoing that upon magnetisation of the core 16, the armature 19 and the finger 20 will be urged in the direction of the arrow 35, but before this movement can occur, the free portion of the finger 20 will be caused to actuate the gear train 28. Accordingly, the closing action of the points 21 and 22 will be "delayed" for a short period of time after the energization of the solenoid, while the finger 20 overcomes the inertia of the gear train 28. Similarly, when supply of current to the solenoid 15 is discontinued, opening of the contact points 21 and 22 will be delayed in the same manner.

Needless to say, the gear 27 may be substituted by a single toothed sector or fork, inasmuch as complete revolution is not required.

Having thus described the structure of the invention, its method of operation will now be explained.

Assuming the engine is to be started, the ignition switch 11 is turned "on," thereby supplying current from the battery 6 to the coil 9 through the conductor 13, the resistor 12 reducing the "delivered" voltage so as to prevent damage to the coil, as already explained.

Thereupon, actuation of the starting switch 8 simultaneously energizes the starting motor 7 and the solenoid 15, the energization of the motor 7 substantially reducing the voltage of the battery 6 within a short period of time after the actuation of switch 8. During this short interval the finger 20 overcomes the inertia of the gear train 28 and closing of the points 21 and 22 is effected, whereupon current from the battery 6 follows a path of least resistance to the coil 9, namely, through the conductors 14 and 18, core 16, armature 19, finger 20, points 21 and 22, and the conductor 23.

Assuming the selector switch 26 to be open, current will pass through the resistor 24, but inasmuch as this resistor is weaker than the resistor 12, current of proper voltage (4½ v.) will be delivered to the coil 9, notwithstanding the operation of the starting motor 7.

It will be apparent that in this manner, an excessive supply of current will be prevented from reaching the ignition coil while the voltage of the battery is being lowered by the starting motor. Similarly, after the starting switch 8 is opened, and supply of current to the motor 7 and the solenoid 15 is discontinued, the "delaying" action of the gear train 28 will maintain the points 21 and 22 in contact for a brief period of time, thereby continuing a supply of relatively high-

voltage current to the coil and thus assisting in the starting of the engine immediately after the switch 8 is opened.

In due course, as the engine is in operation, the points 21 and 22 of course become separated, and current to the coil 9 is delivered through the conductor 13 as aforesaid.

The purpose of the selector switch 26 is to facilitate passage of strong current through the conductor 25 to the coil 9 under winter weather conditions, while the passage of such current may be diverted (by opening the switch) through the resistor 24 in hot weather, when delivery of full voltage to the coil is not necessary.

It is believed that the advantages and use of the invention will be clearly apparent from the foregoing disclosure, and accordingly, further description thereof at this point is deemed unnecessary.

Since various modifications can be made in the invention as hereinafter described, and many apparently widely different embodiments of same made within the spirit and scope of the claim without departing from such spirit and scope, it is intended that all matter contained in the accompanying specification shall be interpreted as illustrative only and not in a limiting sense.

What I claim as my invention is:

A combined ignition and starting motor circuit for internal combustion engines comprising in combination with a battery, starting motor and ignition coil, a magnetically operated switch, a delayed action assembly, a strong resistance and a weak resistance, conductors extending between the foregoing components and switches in said conductors, one of said conductors extending between said battery and said coil, said strong resistance and one of said switches being serially inserted in said conductor, a second conductor having a switch therein extending between said battery and said starting motor, a third conductor extending between said last-mentioned switch and said magnetically operated switch, a fourth conductor extending from a tap on said second conductor upon the starting motor side of the switch therein, to the winding of said magnetically operated switch, a third switch between said magnetically operated switch and said coil, one terminal of said third switch being operatively connected to the armature of said magnetically operated switch, a stationary terminal normally spaced from said first-mentioned terminal, a fifth conductor extending between said stationary terminal and said coil, said weak resistance and a switch being inserted in parallel and in series respectively in said fifth conductor, said delayed action assembly operating to retard the closing of said third switch upon actuation of said magnetically operated switch following the closing of the switch in said second conductor and likewise to retard the opening of said third switch upon the opening of the switch in said second conductor, all for the purpose herein specified.

JOHN BECK.
